GRAVE MARKER

Joseph P. Harner, Nevada, Mo., assignor to The
W. F. Norman Sheet Metal Mfg. Co., Nevada,
Mo.

Application April 23, 1943, Serial No. 484,269

4 Claims. (Cl. 40—124.5)

The object of my invention is to provide a novel grave marker for which the amount of metal required is reduced to a minimum on account of the present shortage of metals for uses other than war purposes.

It is also an object of my invention to provide a grave marker having novel means for securing and holding the marker card in the frame and under glass where it will be protected from the weather, whether made of metal, or wood, or plastic.

It is also my object to provide an efficient and easily operated device for this purpose.

I attain these and other objects of my invention by the means illustrated in the accompanying drawings, in which—

Figure 1 is a front elevation of my invention, a portion of the support being broken away to save space;

Fig. 2 is a vertical section on line 2—2 of Fig. 1;

Fig. 3 is a transverse section on line 3—3 of Fig. 1;

Fig. 4 is a detail perspective view of one form of the trigger or spring catch;

Fig. 5 is an edge elevation of a modified form of the invention in which the card case is mounted at an angle to the post;

Fig. 6 is a front plan view of another modification of the invention in which the post is provided with a slot into which a cross may be inserted for ornamental purposes; and

Fig. 7 is an edge elevation of the form of the invention shown in Fig. 6.

Like numerals designate like parts in each of the several views.

Referring to the accompanying drawings, I provide a pointed post or support 1 to which a preferably wooden back 2 is secured by suitable means as by the nails 3, or by welding or otherwise if a metal back and post are used. On the top and side frame strips 4 and on the recessed portion at the lower ends of the side strips 4 is nailed a bottom frame member 4a, leaving an opening 5 across the bottom of the frame to permit of insertion of the glass or equivalent transparent element 6 and grave marker card 7, as shown in Fig. 2.

In the central portion of the plastic or wooden back 2 I provide a recess 8 beginning about the central portion of the back and increasing in depth to the lower end of the wooden back 2, as shown in Fig. 2.

The spring metal catch 9 has its upper end in-

turned and inserted in a corresponding recess in the wooden back 2 above the upper end of the recess 8, and is also fastened to the wooden back by a suitable nail 12 which is inserted through the opening 11 in the trigger or spring catch 9, or may be fastened by any other suitable means, as by welding, if a metal back is used. At the lower end of the spring catch, two like outwardly turned prongs or projecting folds or equivalent elements 13 of sufficient length to engage under the lower edge of the glass 6 and marker card 7 when they are in place in the frame, are provided. The metal catch also has opposite spaced upper prongs or projecting folds 14 which are shorter than the lower prongs 13 and which press against the back of the marker card 7 to hold it and the glass snugly in place in the frame 4 and 4a, as shown in Figs. 1 and 2. The prongs or folds 13 and 14 are preferably formed integral with the body of the catch 9, as shown.

In use, the spring catch which projects a little at the bottom of the frame, as shown in Fig. 1, is pressed downwardly into the recess 8, thereby permitting of insertion of the marker card 7 and over it the glass 6, after which the spring catch is released and its prongs or projecting folds 13 engage under the glass and its prongs 14 press against the back of the marker card, as shown in Fig. 2. The top and sides of the frame extend to the rear of the frame back 2, as shown in Figs. 2 and 3 and the only opening is at the bottom of the frame at 5 whereby the marker is substantially waterproof, as there is an open space only at the bottom of the frame and the sides and top of the frame completely enclose the glass and marker card, as shown, as the card and glass are inserted from the bottom.

Referring to Fig. 5 there is illustrated a modification of my invention in which the side strips 4 is affixed to the beveled upper end 1a of the post 1 so that the data contained in the card case may be read without stooping over. The structure of the card case is otherwise as heretofore described.

Referring to Figs. 6, 7, there is illustrated another modification of my invention in which the post 1 is provided with a slot 16 at its upper end 50 to receive the reduced lower end 17 of a cross 15. A nail or tack 18 may be inserted, as shown in Fig. 7 to more securely fasten the lower end 17 of the cross 15 in place in the slot 16 of post 1. The cross 15 is preferably of non-metallic material.

The support, back and frame members of the device are preferably made of wood or other non-metallic material at the present time, only the spring catch 9 and nails 3 and 12 being of metal, which is important under war conditions where there is a scarcity of metal for general use in its manufacture, but metal may be used at a future date when it becomes available for general use.

What I claim is:

1. A grave marker consisting of a pointed support, wooden back, top and side frame members secured to the wooden back a relatively narrow frame strip secured in recesses at the bottom of the sides of the frame and leaving an opening at the bottom of the frame, a glass, a marker card insertible through said opening, and a spring catch secured to the back and having prongs engaging the bottom of the glass and the back of the marker card to hold them securely but releasably in place in the device.

2. A grave marker consisting of a pointed non-metallic support, non-metallic back, non-metallic top and side members secured to the non-metallic back, a relatively narrow frame strip secured in recesses at the bottom of the sides of the frame, a glass, a marker card in-

sertible through said opening, and a spring catch secured to the back and having prongs engaging the bottom of the glass and the back of the marker card to hold them securely but releasably in place in the device.

3. In a grave marker, the combination of a post, a back secured to the post, top and side frame members secured to the top and side edges of the back to provide a frame to protect the marker card from the weather at the top and sides, a thin bottom frame member having its ends secured to the side frame members said bottom member being spaced from the back to leave an opening, a glass insertible in the frame through said opening, a marker card insertible through said opening and under the glass, a spring catch having its upper end secured to the back, and having its lower end in spring contact with and shaped to support the glass and marker card in the frame.

4. In combination with the device defined in claim 3, the aforesaid back having a recess increasing in depth toward the bottom edge portion of the back and adapted to allow the spring catch to be pushed to a retracted position against the back.

JOSEPH P. HARNER.
